Chamblani & Newman ATTORNEYS.

UNITED STATES PATENT OFFICE.

THOMAS DIGNEY, OF BRIDGEPORT, CONNECTICUT.

SHADE ROLLER.

1,407,991.

Specification of Letters Patent. Patented Feb. 28, 1922.

Application filed February 21, 1921. Serial No. 446,895.

To all whom it may concern:

Be it known that THOMAS DIGNEY, a citizen of the United States, and resident of Bridgeport, in the county of Fairfield and State of Connecticut, has invented certain new and useful Improvements in Shade Rollers, of which the following is a specification.

This invention relates to new and useful improvements in adjustable window shade rollers and is particularly adapted for use on windows of closed cars such as limousines, sedans, etc.

The object of the invention is to generally improve upon shade rollers of this class and especially to do away with the pivotal forms of pawl mechanism as employed upon the old style of rollers for holding the same in their adjusted position; to lessen the liability of the pawls sticking and thus failing to operate, and especially to avoid rattle which is so liable to come from a pivotal pawl style of roller when used on automobile bodies. Further to provide a more substantial and practical form of automatic holding mechanism.

A further feature of the invention is to provide a series of radially disposed guide slots in the inner face of one of the end members of the roller to accommodate a series of specially formed slidable pawls which engage the shaft to hold the roll in relation thereto and finally to provide a cap to enclose the pawls in operative positions in alignment with the shaft to engage the same and to prevent dust and gas fumes from getting at the pawls.

With these and other objects in view the invention resides and consists in the construction and novel combination and arrangement of parts hereinafter more fully described, illustrated in the accompanying drawings, and pointed out in the claims hereto appended, it being understood that various changes in the form, proportion, size and minor details of construction within the scope of the claims may be resorted to without departure from the spirit or sacrificing any of the advantages of the invention.

Similar characters of reference denote like or corresponding parts throughout the several figures of the accompanying drawings forming a part of this specification, and upon which,

Fig. 1 shows a side view of an improved

form of shade roller constructed in accordance with the objects of my invention.

Fig. 2 is a central vertical longitudinal section of the same.

Fig. 3 is an enlarged vertical longitudinal section through that end portion of the roller including the automatic locking mechanism.

Fig. 4 is a vertical cross section taken on line 4—4 of Fig. 3.

Fig. 5 shows an enlarged detached front elevation and central vertical section of the closure cap employed for covering the pawls, and

Fig. 6 shows upon an enlarged scale, a side and edge view respectively of one of the pawls as shown in Figs. 3 and 4.

Referring in detail to the characters of reference marked upon the drawings, 10 and 11 represent brackets which in practice are attached to the window casing and serve to support the end portions of the roller mounted in sockets of the bracket and to hold the same against turning by reason of the threaded end 12 of shaft 13 engaging the threaded socket in its bracket and holding it against rotation. 14 and 15 represent end members of the roller, each being preferably provided with an annular groove 16 in which the respective ends of the sheet metal barrel 17 of the roller are inserted and soldered or otherwise secured for retaining the parts together.

A torsional spring 18 is mounted upon the shaft and has one of its ends secured at 19 to the end member 14 of the roller and the other end secured at 20 to the roller shaft so as to normally retain the roller in a specially related position to the shaft, but in a way to permit one to be turned with regard to the other against the torsional action of the spring. This much of the mechanism thus described is substantially like that employed in some of the commercial types of shade rollers and does not necessarily form any material feature of my invention.

The specific features of the invention are more particularly shown in Figs. 3, 4, 5 and 6 and in this respect it will be obvious that the above mentioned roller shaft 13 is provided with a notch 21 in the side of one end portion for engagement by means, carried within the roller so as to hold the latter, after the shade has been adjusted, in relation to the fixed position of the shaft. The end member 15 of the roller shown in Figs. 3 and 4, is provided upon its inner side

with an annular shoulder 22 in the peripheral face of which is provided an annular groove 23 while the inner side face of the end member includes a series of radial slots 5 or guideways 24. A sheet metal cap 25 fits over the shoulder and has its edge portion 27 pressed into the annular groove 23 so as to hold the cap in position upon the shoulder and thereby slidably retain the several 10 pawls 26 in said guideways in operative position. These pawls, of which there may be any desired number, four being shown in the drawings, are preferably stamped out of sheet metal, to loosely fit the guide ways referred to and are provided with a tooth upon their inner end suitable to engage the shoulder of the notch in the shaft, that is to say, so that the tooth of the particular pawl positioned above the shaft will engage the notch 20 when the roller is brought to a position of rest, after being quickly adjusted to such position. It will be obvious of course that only one of these pawls engage the shouldered notch of the shaft at one time and 25 that such engagement can only be effected by the particular pawl that happens to be positioned at the top, at the moment when the roller is brought to a stop.

Several small extensions 28 are projected 30 in from the edge of the cap to align with the shoulders 29 of the pawls as shown by full lines in Fig. 3 and as indicated by dotted lines in Fig. 4 and so as to form a stop to limit the forward movement of the pawls 35 and thus prevent them from covering the hole in the end member and interfering with the insertion of the shaft when assembling the rollers. As shown upon one side of the pawls, I provide a series of small projections 40 30 to form a reduced bearing surface for the pawl against the under face of the cap, to prevent the pawls from sticking. These raised bearing points may be produced by 45 punch operations in the opposite side of the pawls.

I claim:

1. In a shade roller, the combination with a spring actuated barrel and a longitudinal shaft contained therein having a shouldered notch adjacent one end, of an end member 50 for closing the barrel and having a hole to rotatably receive the shaft, including a hub portion extending into the barrel and having a series of guide-ways adapted to register successively with said notch in the rotation of said barrel, a series of pawls slidably mounted in said guideways, and a cap fitted upon the hub of the end member for enclosing the pawls, said end member provided with an annular shoulder in the peripheral face of which is an annular groove, and said cap having its edge portion pressed into 55 said annular groove.

2. In a shade roller, the combination with a spring actuated barrel and a longitudinal 60 shaft contained therein having a shouldered notch, of an end member for closing the barrel and having a hole to rotatably receive the shaft, including a hub portion extending into the barrel and having a series of guide 65 ways surrounding the notched end portion of the shaft, a series of pawls slidably mounted in said guide ways to engage the shaft, and a cap fitted upon the hub of the end member for enclosing the pawls, said 70 end member provided with an annular shoulder in the peripheral face of which is an annular groove, and said cap having its edge portion pressed into said annular groove, and the body of said cap having extensions projecting therefrom and into the path of operation of the pawls to limit the movement of the same.

Signed at Bridgeport in the county of Fairfield and State of Connecticut this 19th 85 day of February, A. D. 1921.

THOMAS DIGNEY.
